UNITED STATES PATENT OFFICE.

NILS TESTRUP, OF WESTMINSTER, LONDON, AND TEOFRON BOBERG, OF CLAPHAM PARK, LONDON, ENGLAND, ASSIGNEES TO TECHNO-CHEMICAL LABORATORIES LIMITED, OF LONDON, ENGLAND.

DRYING OR EVAPORATING SURFACE OR THE LIKE.

Application filed October 4, 1922. Serial No. 592,348.

To all whom it may concern:

Be it known that we, NILS TESTRUP, a subject of the King of Great Britain and Ireland, and residing at 47 Victoria Street, 5 Westminster, London, S. W. 1, England, and TEOFRON BOBERG, a subject of the King of Sweden, and residing at Fairlawn, Clarence Road, Clapham Park, London, S. W. 4, England, have invented certain new and 10 useful Improvements in or Relating to Drying or Evaporating Surfaces or the like, of which the following is a specification.

This invention relates to processes or apparatus of the type in which moist material 15 is applied in a film or layer upon a surface for the purpose of facilitating the transmission of heat thereto as, for example, in drying or other heat treatment processes.

Such operations are frequently carried 20 out upon the smooth surface of a drum to which a heating medium is supplied while it is rotated, and when the material undergoing treatment is in a sufficiently liquid state a film of it may be applied by allowing the under side of the drum to dip into matter in a suitable trough, or with matter 25 in a more pasty or plastic condition, rollers, spreaders or like squeezing means have been employed for compelling a film of the matter to adhere to the surface of the drum; such expedients, however, are only satisfactory 30 within certain limits of liquid content or kinds of matter and the formation and retention of a film upon a surface often becomes difficult under altered conditions.

Obviously it is desirable to provide as much heating surface as possible in an apparatus of given size or cost and for this purpose it has been proposed to employ two 40 drums arranged side by side and squeezing the matter between them so as to form simultaneously a layer upon both drums, but this again will only apply to certain materials or conditions thereof and materials which are difficult to spread upon a moving heating surface in a self-retaining or adhesive film such, for example, as macerated peat of limited liquid content, lignite and the like cannot be satisfactorily dealt with in this manner.

The object of the present invention is to overcome the foregoing difficulties and pro-

vide for the ready filming to any desired extent of materials of the type indicated.

The invention consists in a method of applying and maintaining matter in uniformly and thinly distributed quantities upon a surface for the purpose of imparting heat thereto according to which the matter is filled into a series of grooves or 60 indentations so formed as to effectively retain the matter upon the surface during the operation.

The invention further consists in apparatus for applying heat, say for example for 65 drying, to matter distributed upon a surface in which said surface is provided with closely adjacent and uniformly distributed grooves, indentations or the like having sides so disposed as to ensure the desired re- 70 tention of the material.

The invention further consists in apparatus as indicated in which the surface, say for example of a rotatable hollow drum, is 75 formed with a series of small closely spaced parallel grooves which are more or less rectangular or parallel sided in cross-section at or near the bottom and flared at the top so that the adjoining sides of adjacent grooves meet in an intermediate ridge or the like. 80

The invention further consists in apparatus for forming layers of moist material for the purpose of transmitting heat thereto, in which material is squeezed between a pair of rotating drums and is caused to adhere in a uniform manner to a large extent of surface by the provision of suitably shaped grooves in the two co-operating drum surfaces.

The invention further consists in apparatus as indicated in which the material is suitably spread for heat transmission by a moderate temperature difference such, for example, as may be obtained when re-utilizing the latent heat of the vapour of an 90 evaporating process or other waste or moderate temperature heat, by means of grooves which are so shaped that the material is sufficiently wedged therein by the co-operation of the two drums to effect its division 95 in a uniform manner between the two surfaces thereof.

The invention also consists in improvements in or relating to spreading moist ma-

terial upon heat transmitting or other surfaces as hereinafter indicated.

Referring now to the accompanying more or less diagrammatic drawings:—

5 Figure 1 is a diagrammatic representation of two co-operating drums within a casing;

Figure 2 shows the arrangement in plan view;

10 Figure 3 shows to a considerably enlarged scale a section of the grooves on a pair of co-operating drums;

15 Figure 4 shows one condition of adjustment of the grooves of the two drums relative to one another;

Figure 5 shows another condition of adjustment;

20 Figure 6 is a fragmental diagrammatic sketch showing a single drum and a plain feed roller;

25 Figure 7 is a fragmental diagrammatic sketch showing two drums and a dividing plate between them, and

Figure 8 is a fragmental diagrammatic sketch showing a drum with longitudinal grooves and a brush or like dislodging or removal means.

30 Figure 9 shows a modified form of the grooves and ridges.

35 In the convenient arrangement shown by way of example in Figures 1 and 2, *a* is an enclosed casing within which are mounted two co-operating hollow drums *b*, *b'* having circumferential grooves upon their external surfaces.

40 The drums *b*, *b'* are provided with hollow trunnions carried in bearings *c*, *c'* and *d*, *d'*, the former of which are adjustable in a horizontal direction to regulate the distance between the axes or peripheries of the drums and the latter of which are adjustable in an axial direction to adjust the relationship of the grooves of one drum relative to those of the other.

45 The drums are both positively driven at the same speed and in opposite rotational directions by means such as those represented diagrammatically in the drawings, such means comprising a pulley *e*, meshing toothed 50 wheels *f*, *f'*, chain wheel *g*, *g'*, *h*, *h'* and chains *g*² and *h*² co-operating therewith.

55 Means such as a hopper or the like *i* are provided for feeding into the casing between the two drums the material which is to be treated and which after treatment is removed by scrapers *j*, *j'* which may co-operate with troughs containing helical conveyors *j*², *j*³ for removing the treated material.

60 In the case of a drying apparatus the drums are in the first instance heated by live steam admitted by a suitable connection to the hollow trunnions *c*, *d*, and as vapour is evolved from the material upon the surface of the drums this is drawn off through the pipe *l* by the compressor *k* and delivered at a

sufficiently increased pressure and temperature to the interior of the drums by the pipe *m*, supplies of live steam being meanwhile reduced until it is only sufficient for make-up purposes.

70 The circumferential surfaces of the two drums are provided with a series of closely adjacent circumferential grooves, as shown in Figure 3, and of which say from ten to fourteen may be formed in each linear inch of the drum length. The grooves may have a total depth somewhere in the neighbourhood of about two-thirds of the pitch and the lower portions of the sides of the grooves, namely the portions marked *n*, *n'*, may be 75 parallel or substantially parallel with one another so that the bottom of the grooves is rectangular with a width preferably equivalent to about one-half of the pitch.

80 The upper portions of the sides of the grooves, namely those marked *n*², *n*³, are bevelled for about one-half of the total depth of the groove so that the upper portion of the groove is flared outwards in such a manner that the edges of adjacent grooves 85 meet in a V-shaped ridge midway between the two grooves. The bevelling of the flared portion may be at an angle of about 60° to the axes of the drums.

90 In most instances it is found that the best results are obtained when the ridges of one surface are set opposite to the centres of the grooves of the other surface, as shown in Figure 4, this being accomplished by adjustment of the bearings *d*, *d'*. The axes of the 95 drums may also be adjusted in relation to one another so that the ridges of one drum enter the grooves of the other to any desired extent, say for example as shown in Figure 5, the amount of entry depending upon the 100 nature of the material and/or upon the liquid content thereof.

105 With grooves as hereinbefore described the material fed into the space where the two drums are approaching one another is so 110 wedged into the cavities or grooves as to present when in the initial condition of moisture a moderate resistance to being withdrawn, and this resistance will be greater than the resistance to separation of the layer 115 of material into two halves upon a plain or other contour surface running from ridge to ridge of the projections between the cavities. The determined layer of material squeezed between the two drums will, therefore, be divided equally between them and be distributed in a uniform manner over the entire heating surface of the two drums.

120 Although the material is wedged in the cavities or grooves this wedging is not sufficient to prevent its removal by toothed scraping devices, such as shown at *j*, *j'* brushes or the like at any desired location after the material has travelled with the drums through any desired portion of a revolution, 125 130

this being particularly the case when actual evaporation in contradistinction to mere heating is taking place, as the bulk of the material will naturally be reduced by the liquid driven off as vapour.

The invention offers particular facilities for the expulsion of a considerable part of the liquid content of a material as the process may be carried out in a series of stages 10 or separate pairs of drums, each of which is suitably proportioned to the volume of the material at any particular liquid content, the actual condition of the material as to adhesion or friability being practically immaterial as the grooves may be set in the correct relationship to one another to be capable of dealing with materials of very different consistencies.

In the arrangement shown in Figure 6, a 20 single grooved drum *o* is shown in conjunction with a plain feed roller *p* of smaller diameter than the drum, this arrangement being convenient in some cases where the obtaining of a maximum surface for a given 25 size of plant is not so essential. The material is when treated removed by a scraper or brush *q* into the trough *q'* from which it is taken by suitable means.

In some instances a grooved drum may be 30 used in conjunction with a spreading plate, or preferably as shown in Figure 7, a spreading plate *r* may be inserted in the feed space between two grooved drums *s*, *s'* which ensures that the pressure to which the material 35 is subjected is the same upon both sides of the plate.

Figure 8 shows an arrangement of longitudinal grooves running parallel with the axis of the drum, and this arrangement, or 40 grooves disposed at any other angle upon the circumferential surface of the drum, may be desirable in certain connections.

Grooves of this type may be arranged to 45 operate in conjunction with a pressing plate *r'* or a plate may be inserted between two drums, as already described; the grooves 50 may be of similar shape to the circumferential grooves previously described and a brush is preferably employed for the removal of the material from the grooves after 55 the desired treatment.

The flared portion of the grooves may 60 be curved as shown in Figure 9 and instead of a V-shaped ridge the shape of the ridge 55 may be rounded. So long as a substantially parallel sided region is provided in at least some of the length of the grooves as shown at *n*⁴, *n*⁵, the upper portion following a curve say of radius *x*.

65 The method of heating hereinbefore described is in accordance with our British Patent No. 149055, but the invention is by no means restricted to this type of heating and may be employed in connection with many of our prior proposals, and any hot,

gaseous or other fluid may be employed either within or upon the outside of the drum surfaces.

In connection with the drying of lignite exhaust steam, say, at about 130° C. may 70 often be available in sufficient quantities to perform the whole of the drying, and in such instances this steam may be supplied to the interior of a pair of drums and after being condensed therein may be returned 75 as boiler feed. A temperature of say, 115° C. may be maintained in the casings and the evolved vapour at this temperature may be taken to another pair of drums upon which drying is also carried out, thus effecting a considerable economy. Similarly, suitable conditions may also apply in connection with the drying or other heat treatment 80 of many other materials.

Drums of this type may be operated upon 85 the multiple effect principle described in our British Patent Application No. 16818 of 1922, or the drums may be heated externally or internally by hot waste gases or any other convenient source of heat.

90 The invention offers special facilities for heat treatment with small temperature differences as the uniform and even films or layers which may be obtained thereby are more readily acted upon in a satisfactory 95 manner. The complete operation of dispelling a large quantity of liquid from the material may also be divided up into a plurality of stages as the condition of the material in the different stages will not hinder 100 the formation of satisfactory films because the grooving ensures the retention of material of practically any desired liquid content and it is possible by means of the invention to treat lignite for drying, say from a water content of about 50% down to a water content of as low as 48% if required.

105 By means of this invention it is not only possible to retain in uniformly distributed quantities upon the drying surface material 110 of a friable or like nature which could not without great difficulty be made to adhere to a plain surface, but the additional area afforded by the contour of the grooves provides a much greater surface for the 115 transmission of heat from the material of the partition or wall into the matter undergoing treatment, and in view of this feature greatly increased output may be obtained from a given size of drum or other 120 evaporating surface.

125 The last-mentioned feature also renders the invention particularly useful in connection with evaporating processes where the matter remains in a liquid state throughout the process, as not only is the heat transmitting surface greatly increased, but a given size of drum is capable of picking up from an underlying trough or the like 130 a much greater quantity of liquid than may

be picked up by a plain drum surface, the ratio being in the nature of from $1\frac{1}{2}$ to $2\frac{1}{2}$ times for the form of groove hereinbefore indicated.

- 5 The invention may be applied either to the heating only of materials, particularly where this is carried out at small temperature differences, such as are obtainable when utilizing waste heat or to drying, particularly where this is effected by re-utilizing the latent heat of the evolved vapour either by compression or in any other way.

It is to be understood that the apparatus and applications thereof hereinbefore described are given by way of example only, and that modifications and additions may be introduced without in any way departing from the spirit of this invention.

Having now particularly described our invention what we claim as new and desire to secure by Letters Patent is:—

1. Apparatus for applying heat to matter distributed upon a surface, said surface having grooves therein with at least some parallel sided region in the lower portions and flaring sided upper portions.

2. Apparatus for applying heat, say for example for drying, to matter distributed upon a surface, in which said surface is provided with closely adjacent and uniformly distributed grooves, each having a cross-sectional configuration the sides of which are parallel to one another in at least some region at or near the bottom and flared apart at a wider angle at the top.

3. Apparatus for applying heat say for example for drying the matter distributed upon a surface, in which the surface of a rotatable hollow drum is formed with a series of small closely spaced parallel grooves which are parallel-sided in cross-section at or near the bottom and flared at the top so that the adjoining sides of adjacent grooves meet in an intermediate ridge or the like.

4. Apparatus according to claim 3 for forming layers of moist material for the purpose of transmitting heat thereto, in which material is squeezed between a pair of rotating drums and is caused to adhere in a uniform manner to a large extent of surface by the provision of suitably shaped grooves in the two co-operating drum surfaces.

5. Apparatus according to claim 3 with a pair of rotating drums between which the material is squeezed, in which the material is suitably spread for heat transmission thereto by a moderate temperature difference, such for example as may be obtained when re-utilizing the latent heat of the vapour of an evaporating process or other waste or moderate temperature heat, by means of grooves which are so shaped that the material is sufficiently wedged therein

by the co-operation of the two drums to effect its division in a uniform manner between the two surfaces thereof.

6. In apparatus for spreading moist material on a surface for transmitting heat thereto, the provision in said surface of grooves or the like having sides which are in some measure parallel or slightly inclined to one another to ensure sufficient retention of the material to complete the desired heat treatment without undesirable disengagement.

7. Apparatus for forming layers of moist material and transmitting heat thereto comprising in combination a pair of rotatable hollow drums arranged side by side, a series of closely adjacent and similar circumferential grooves having at least some portion of their sides parallel to one another formed in said drum surfaces, means for adjusting the distance between the axis and the relative longitudinal positions of said drums to secure any desired co-operation of said grooves and their intermediate ridges, means for feeding in material to be squeezed between said drums into said grooves, means for imparting heat to said material, and means for removing the material from said grooves when treated.

8. Apparatus according to claim 2, in which the evolved vapours raised in pressure and temperature so as to recover the latent heat thereof are employed as the medium for imparting heat to the material.

9. Apparatus according to claim 3 with a pair of rotating drums between which the material is squeezed, in which ridges between the grooves of one drum of a pair are more or less approximately complementary to or adapted to enter the grooves of the other drum and vice versa and means are provided for adjusting the relationship of the two drums to secure any desired degree of co-operation between their grooves and ridges.

10. Apparatus for forming layers of moist material and transmitting heat thereto comprising in combination a pair of rotatable hollow drums arranged side by side, a series of closely adjacent and similar circumferential grooves having at least some portion of their sides parallel to one another formed in said drum surfaces between intermediate ridges, means for adjusting the distance between the axis and the longitudinal position of one of said drums relative to the other to secure any desired co-operation of said grooves and their intermediate ridges, means for feeding in material to be squeezed between said drums into said grooves, means for imparting heat to said material, a compressor for withdrawing the vapours evolved from the material and after reducing its volume returning it at a higher temperature to the interior of the drums, and means

for removing the material from said grooves when treated.

11. Apparatus according to claim 3, in which a pair of drums having grooved surfaces are separated by an intermediate smooth surfaced plate, small roller or the like which is pressed between the drums and supported thereby so that it is rendered sufficiently rigid to spread a smooth surface faced layer on each drum, although it is itself only of comparatively light construction.

12. Apparatus according to claim 3, in which the proportions of the grooves are

determined so as to spread a very thin and uniform layer over substantially all the heating surface, and at the same time retain the material even when it has reached a comparatively low liquid content in order that the small temperature increase which can be economically obtained when employing the expedient of heating with the evolved vapours after compression thereof may be utilized to effect the drying operation.

In testimony whereof we have signed our names to this specification.

NILS TESTRUP.
TEOFRON BOBERG.
